UNITED STATES PATENT OFFICE.

HARRY LANDSIEDEL, OF CINCINNATI, OHIO, ASSIGNOR TO THE DALTON ADDING MACHINE COMPANY, OF CINCINNATI, OHIO, A CORPORATION OF OHIO.

ADDING AND RECORDING MACHINE.

1,400,610.

Specification of Letters Patent. Patented Dec. 20, 1921.

Application filed May 12, 1919, Serial No. 296,323. Renewed December 24, 1920. Serial No. 433,052.

To all whom it may concern:

Be it known that I, HARRY LANDSIEDEL, a citizen of the United States, residing at Cincinnati, county of Hamilton, and State of Ohio, have invented a new and useful Adding and Recording Machine, of which the following is a specification.

This invention relates to adding and recording machines.

10 In the recording operation of the type-carriers in adding machines it is often necessary to move the different type-carriers varying distances to place them in position to support the type for recording properly. 15 For this purpose each type-carrier is provided with an individual actuating device, usually a spring, and these springs are all energized at each operation of the controlling shaft of the adding machine. Thus, 20 assuming that the machine includes nine type-carriers and a separate actuating spring for each type-carrier, all of said springs have heretofore been energized at each operation of the controlling shaft, whether all of the 25 type-carriers were operated or not. Therefore, if only one, two or three of the type-carriers for instance were operated, the machines have nevertheless required the tensioning or energizing of all of the springs for 30 actuating all of the type-carriers. It is obviously undesirable to tension or energize springs whose type-carriers are not placed in operation, because such unnecessary operation requires more power than would be 35 required if only the necessary number of springs were placed under tension, and also results in unnecessarily weakening the springs.

My present invention overcomes the objections mentioned. I have provided each type-carrier with an individual actuating spring and means properly controlled as an incident to operation of the controlling shaft for tensioning or energizing the springs whose 45 type-carriers are required to operate while leaving the springs for the remaining type-carriers normal or without increase of energy or tension. It is appropriate to mention that all of the type-carrier actuating 50 springs normally have a predetermined degree of energy or tension and that the energy or tension of the springs whose type-carriers are to operate is increased as an incident to operation of the controlling shaft,

whereas the energy or tension of the springs 55 whose type-carriers are not to operate remains unchanged.

The object of my invention is to provide efficient mechanism for accomplishing the results above mentioned and those hereinabove more particularly set forth; and with the foregoing and other objects in view I have illustrated one embodiment of my invention in the accompanying drawings, in which—

Figure 1 is a sectional view of an adding 65 and recording machine containing the invention.

Fig. 2 is a plan view showing the location and arrangement of the spring tensioning 70 devices.

Fig. 3 is a perspective view more clearly illustrating parts of the invention.

Fig. 4 is a detail view showing portions of type-carriers in advance positions and whose spring tensioning devices are positioned for 75 operation.

Fig. 5 is a somewhat similar view showing the spring tensioning devices after they have been operated to advance the connected type-carriers.

By reference to the drawings, it will be recognized that I have illustrated my invention in a machine containing differential mechanism substantially like that contained in the Dalton adding machine, which is 85 manufactured under Hubert Hopkins Patent No. 1,039,130, dated September 12, 1912.

In the machine illustrated numbers are set up in a laterally movable carriage 1. The type-carriers 2 are pivotally supported by a 90 rock shaft 3 and are controlled in their recording operations by the stops set up in the carriage 1. The type-carriers 2 are cooperatively associated with racks 2^a which actuate the adding wheels 2^b in adding and clearing operations. The machine includes a controlling shaft 4 which is a rock shaft and from which a train of connections comprising a link 5 and an arm 6 leads to the rock shaft 3. When any number is to be recorded 95 the same is set up in the differential mechanism contained in the carriage 1 after which the controlling shaft 4 is turned in a forward direction, thus also turning the shaft 3 by the connections from the shaft 4 comprising the link 5 and the arm 6.

Each type-carrier is formed with a rearwardly extended arm 7 which is connected

to the adjacent coöperating rack 8 also swinging from the shaft 3 by a spring 9 whose tendency is to actuate the type-carrier and the associated rack in opposite directions. A spring 10 connects each arm 7 with a tensioning member 11. The tensioning members 11 are movable through openings in a guide plate 12 and are further guided in their movements by a guide 13. Each tensioning member 11 is formed with a shoulder 14 arranged to engage the guide plate 12 and limit upward movement of the tensioning members. In this way the tensioning members will be held in position in which the springs 10 are slightly energized to impart an initial movement to the corresponding type-carrier when the controlling shaft is operated.

My invention further comprises mechanism for actuating the energizing members 11 as required to energize the springs of the type-carriers which it is desired to operate.

As clearly shown in Fig. 3 two arms 15 are attached to the rock shaft 3. Each of said arms 15 is provided with a vertical extension 16. A link 17 is pivoted to each of the extensions 16, said links being guided in their movements by the guide plate 12 through which said links extend. Each of the links 17 is formed with a forwardly extended arm 18, the same being connected with the rear ends of the arms 15 by retractile springs 19. It is obvious that the tendency of the springs 19 as to actuate the lower ends of the links 17 rearwardly. In the normal or idle position of the machine the links 17 are held in their forward positions by cams 20 thereon contacting with the walls of the slots in the guide plate 12 through which said links extend. The lower ends of the links 17 are connected by a cross member 21 which moves up and down with the links as said links are moved up and down as a result of operation of the controlling shaft 4.

In the normal or idle position of the machine as illustrated in Fig. 1, the shoulders 14 on the tensioning members 11 are in contact with the lower side of the guide plate 12 and the member 21 is supported some distance above shoulders 22 on the lower ends of the tensioning members. In the normal or idle position of the machine the tensioning members are held in proper position in this instance in vertical position, by projections 23 on the type-carriers engaging the upper extremities of said tensioning members.

The type-carriers are held in their idle positions, and are returned to their idle positions after each operation, by an appropriate device provided for that purpose which, in the form shown, is a bail. As shown the bail comprises a rod 24 supported by the arms 15 under the extremities of the arms 7

of the type-carriers, and a tubular sleeve 25 revolvably mounted on said rod.

As will be understood by reference to Fig. 1, the springs 10 extend upwardly and forwardly from the upper ends of the tensioning members 11, thus tending to move the tensioning members to inclined positions. Such tendency of the springs 10 to move the tensioning members to inclined positions is resisted by the projections 23 when the type-carriers are in their normal or idle positions.

However, when any of the type-carriers move forwardly to recording positions the projections 23 are carried away from the tensioning members 11, whereupon the springs 10 connected with the type-carriers which have moved forward, move the corresponding tensioning members to inclined position as shown in Fig. 4, placing the shoulders 22 of said tensioning members in position to be engaged by the cross member 21.

Further movement of the controlling shaft 4 moves the arm 6 to the position shown in Fig. 5. As before stated the arm 6 is attached to the shaft 3, which is a rock shaft, so that said shaft 3 is turned by the arm 6. Turning of the shaft 3 also lowers the arms 15 from their normal or idle positions shown in Fig. 1 to lower positions shown in Fig. 5, thereby moving downwardly the links 17 and the connecting cross member 21.

The cross member 21 engages the shoulders 22 of the tensioning members whose type-carriers have moved forwardly, it being understood that the tensioning members corresponding to the type-carriers which remain stationary are not engaged by the cross member 21. This is because the tensioning members 11 corresponding to the type-carriers which remain idle or stationary are held in their vertical positions by the projections 23 on the stationary type-carriers; so that upon slight downward movement of the links 17 the shoulders 20 thereon are moved below the guide plate 12 whereupon the lower ends of said links 17 are moved rearwardly to the positions shown in Fig. 4. This rearward movement of the lower ends of the links 17 is caused by the springs 19 as before stated, and such rearward movement is sufficient to place the cross member 21 rearwardly from the projections 22 of those tensioning members which are held in their normal or idle positions by the corresponding idle type-carriers.

Therefore, when the links 17 are moved downwardly the cross member 21 will not engage with the tensioning members corresponding to the idle type-carriers, but will engage with the tensioning members which are connected with the operating type-carriers. Downward movement of the links 17 is continued until said links are moved to the positions shown in Fig. 5, the tensioning members 11 cor-

responding to the type-carriers that were operated being moved also to the positions shown in Fig. 5. This movement of the tensioning members 11 stretches and energizes the springs connecting them with their respective type-carriers so that said springs will actuate the type-carriers to their proper recording positions.

From the foregoing it will be understood that the only springs corresponding to the type-carriers that are operated are energized or placed under tension as an incident to operation of the controlling shaft and its associated mechanism. This prevents needless operation or energizing of the springs which are not required to function during the respective operations of the machine. The advantage of this result is obvious.

The invention is not dependent upon the cross carriage type of differential mechanism, but may be used with equal success in other machines. Therefore, I do not restrict myself to the use of the invention in a machine possessing any particular form of differential mechanism, but desire to claim the invention in any embodiment in which it may be successfully employed.

I claim—

1. An adding and recording machine, comprising type-carriers, a rock shaft controlling the operation of said type-carriers, springs for actuating said type-carriers respectively, and mechanism for energizing springs corresponding to the type-carriers that are to be operated as an incident to operation of said rock shaft.
2. In an adding and recording machine, comprising type-carriers, a bail device controlling operation of said type-carriers, a spring for actuating each type-carrier, means for operating said bail device, and means for energizing the springs corresponding to the type-carriers that are to be operated as an incident to operation of said bail device.
3. In an adding and recording machine, type-carriers, a rack associated with each type-carrier, differential mechanism coöperating with said racks to limit movement of the type-carriers and determining which of said type-carriers may be operated, a spring for actuating each type-carrier and thereby its associated rack, and a tensioning device for each of said springs.
4. In an adding and recording machine, type-carriers, a rack associated with each type-carrier, differential mechanism coöperating with said racks to limit movement of the type-carriers and determining which of said type-carriers may be operated, a spring for actuating each type-carrier and thereby its associated rack, a tensioning device for each of said springs, and an actuator for said tensioning devices.
5. In an adding and recording machine, a series of type-carriers, a series of racks cor-
- responding to said type-carriers respectively, a spring connecting each rack with the corresponding type-carrier, a spring connected with each type-carrier for actuating the same and thereby the corresponding rack, a tensioning member connected to each of said last-named springs, and a device for actuating said tensioning members to energize said springs selectively.
6. In an adding and recording machine, a series of type-carriers, a series of racks corresponding to said type-carriers respectively, a spring connecting each rack with the corresponding type-carrier, a spring connected with each type-carrier for actuating the same and thereby the corresponding rack, a tensioning member connected to each of said last-named springs, a device for actuating said tensioning members to energize said springs selectively, and means controlled by said type-carriers determining which of said tensioning members may be actuated.
7. In an adding and recording machine, a type-carrier, a spring connected with said type-carrier, a tensioning device connected to said spring, an actuator for actuating said tensioning device to energize said spring, and an element controlled by the type-carrier for holding said tensioning device in its idle position.
8. In an adding and recording machine, a type-carrier, a spring connected with said type-carrier, a tensioning device connected to said spring, an actuator for actuating said tensioning device to energize said spring, and an element controlled by the type-carrier for holding said tensioning device in its idle position and controlling the operation of said tensioning device by said actuator.
9. In an adding and recording machine, a rack, a spring for actuating said rack, a tensioning device for energizing said spring as required to actuate said rack, an actuator for operating said tensioning device as required to energize said spring, a type-carrier associated with said rack, and means controlled by said type-carrier determining when said tensioning device may be operated to energize said spring.
10. In an adding and recording machine, a series of type-carriers, a bail holding said type-carriers in their idle positions, a spring in connection with each type-carrier for actuating the same, a tensioning device for energizing each of said springs, mechanism for limiting movement of said type-carriers, and means controlled by said type-carriers respectively for preventing the operation of the tensioning devices corresponding to the type-carriers that are to remain idle, and for permitting operation of the tensioning devices whose type-carriers are to operate and be limited in their movements by said movement limiting mechanism.
11. In an adding and recording machine,

1. A series of type-carriers, springs for operating said type-carriers respectively, a tensioning device in connection with each of said springs, an actuator for actuating said tensioning devices to energize said springs, and means controlled by the type-carriers for holding said tensioning devices out of position to be engaged by said actuator when said type-carriers are in their idle positions.
2. In an adding and recording machine, a series of type-carriers, springs for operating said type-carriers respectively, a tensioning device in connection with each of said springs, an actuator for actuating said tensioning devices to energize said springs, and means controlled by the type-carriers for holding said tensioning devices out of position to be engaged by said actuator when said type-carriers are in their idle positions,
3. In an adding and recording machine, 15 tensioning devices to energize said springs, and means controlled by the type-carriers for holding said tensioning devices out of position to be engaged by said actuator when said type-carriers are in their idle positions,
4. In an adding and recording machine, 20 and permitting said tensioning devices to be moved by said springs to position to be engaged by said actuator after slight movement of said type-carriers.
5. In an adding and recording machine, 25 type-carriers, actuating springs in connection with the type-carriers respectively, a tensioning device in connection with each of said springs, means for holding said tensioning devices in position to energize said springs slightly when said type-carriers are in their idle positions, and an actuator for actuating said tensioning devices to increase the tension and energy of said springs as an incident to movement of said type-carriers from their idle positions.
6. In an adding and recording machine, 30 type-carriers, springs connected to said type-carriers for actuating the same, a tensioning member in connection with each of said springs for energizing said springs, guides in which said tensioning members are movable, an abutment on each tensioning member for limiting movement thereof in one direction, and an actuator for actuating said tensioning members selectively to energize selected ones of said springs.
7. In an adding and recording machine, 35 type-carriers, springs connected to said type-carriers for actuating the same, a tensioning member in connection with each of said springs for energizing said springs, guides in which said tensioning members are movable, an actuator for actuating said tensioning members selectively to energize selected ones of said springs, and means for determining which of said tensioning members may be actuated.
8. In an adding and recording machine, 40 type-carriers, a bail holding said type-carriers in their idle positions, a spring connected to each type-carrier for actuating the same, tensioning members operable to energize said springs, and mechanism operated as an incident to movement of said bail for actuating selected ones of said tension-
9. In an adding and recording machine, 45 type-carriers, a device holding said type-carriers in their idle positions, mechanism for determining which of said type-carriers may be operated, a spring connected to each type-carrier, and mechanism under control of the type-carriers for energizing said springs selectively.
10. In an adding and recording machine, 50 type-carriers, a device holding said type-carriers in their idle positions, mechanism for determining which of said type-carriers may be operated, a spring connected to each type-carrier, and mechanism under control of the type-carriers for energizing said springs selectively.
11. In an adding and recording machine, 55 type-carriers pivoted on said shaft, a bail supported by said shaft holding said type-carriers in their idle positions, springs connected to said type-carriers for actuating the same, and means under control of said type-carriers and said bail for selectively energizing said springs.
12. In an adding machine, the combination with adding wheels, racks for actuating said wheels, and springs for actuating said racks in one direction, of a tensioning member in connection with each of said springs, an actuator for actuating said tensioning members to energize said springs selectively, and means for selectively connecting the tensioning members with said actuator.
13. In an adding machine, adding wheels, 60 racks for actuating said wheels, differential mechanism coöperating with said racks to limit movement thereof in one direction and determining which of said racks may be moved, a spring for actuating each of said racks, an independent tensioning device for each of said springs, and an actuator for said tensioning devices.
14. In an adding machine, adding wheels, 65 racks for actuating said wheels, a rock shaft controlling the operation of said racks, springs for actuating said racks selectively, and mechanism for energizing said springs corresponding to the racks that are to be operated as an incident to the turning of said rock shaft in one direction.
15. In an adding machine, adding wheels, 70 a series of racks for actuating said wheels, a bail device controlling the operation of the racks, a spring for actuating each rack, means for operating said bail device, and means for energizing the springs corresponding to the racks that are to be operated as an incident to the movement of said bail device in one direction.
16. In an adding machine, adding wheels, 75 a number of racks for actuating said wheels, differential mechanism for limiting movement of said racks, springs for actuating said racks respectively, and means for energizing the springs corresponding to the racks that are to be operated at any operation of the machine while leaving undisturbed the springs corresponding to the racks that are to remain idle.
17. In an adding and recording machine, 80 type-carriers, a device holding said type-carriers in their idle positions, mechanism for determining which of said type-carriers may be operated, a spring connected to each type-carrier, and mechanism under control of the type-carriers for energizing said springs selectively.
18. In an adding and recording machine, 85 a rock shaft, type-carriers pivoted on said shaft, a bail supported by said shaft holding said type-carriers in their idle positions, springs connected to said type-carriers for actuating the same, and means under control of said type-carriers and said bail for selectively energizing said springs.
19. In an adding machine, the combination with adding wheels, racks for actuating said wheels, and springs for actuating said racks in one direction, of a tensioning member in connection with each of said springs, an actuator for actuating said tensioning members to energize said springs selectively, and means for selectively connecting the tensioning members with said actuator.
20. In an adding machine, adding wheels, 90 racks for actuating said wheels, differential mechanism coöperating with said racks to limit movement thereof in one direction and determining which of said racks may be moved, a spring for actuating each of said racks, an independent tensioning device for each of said springs, and an actuator for said tensioning devices.
21. In an adding machine, adding wheels, 95 a series of racks for actuating said wheels, a rock shaft controlling the operation of said racks, springs for actuating said racks selectively, and mechanism for energizing said springs corresponding to the racks that are to be operated as an incident to the turning of said rock shaft in one direction.
22. In an adding machine, adding wheels, 100 a series of racks for actuating said wheels, a bail device controlling the operation of the racks, a spring for actuating each rack, means for operating said bail device, and means for energizing the springs corresponding to the racks that are to be operated as an incident to the movement of said bail device in one direction.
23. In an adding machine, adding wheels, 105 a number of racks for actuating said wheels, differential mechanism for limiting movement of said racks, springs for actuating said racks respectively, and means for energizing the springs corresponding to the racks that are to be operated at any operation of the machine while leaving undisturbed the springs corresponding to the racks that are to remain idle.
24. In an adding machine, adding wheels, 110 a number of racks for actuating said wheels,

a spring for actuating each of the racks in one direction, a tensioning device for each of said springs, and means for operating said tensioning devices corresponding to the 5 racks that are to be operated but leaving undisturbed the tension devices of the springs corresponding to the racks that are not to be operated.

25. In an adding machine, adding wheels, 10 a series of racks for actuating said wheels, a

bail holding said racks in their idle positions, a spring for operating each of said racks, a tensioning device for energizing each of said springs, mechanism for limiting movement of said racks, and means for preventing operation of the tensioning devices corresponding to the racks that are to remain idle. 15

HARRY LANDSIEDEL.
